UNITED STATES PATENT OFFICE.

THOMAS F. RAINSFORD, OF DETROIT, MICHIGAN, ASSIGNOR OF ONE-FOURTH TO
THOMAS C. WHITEHEAD, OF RIVER ROUGE, MICHIGAN.

DESIGN FOR AN AUTOMOBILE RADIATOR.

Application filed December 17, 1925. Serial No. 15,775. Term of patent 14 years.

To all whom it may concern:

Be it known that I, THOMAS F. RAINSFORD, a citizen of the United States, residing at Detroit, in the county of Wayne and State of Michigan, have invented a new, original, and ornamental Design for Automobile Radiators, of which the following is a specification, reference being had to the accompanying drawings, forming part thereof.

In the drawings:

Figure 1 is a front elevation of the automobile radiator showing my new design, and Figure 2 is a side elevation thereof.

I claim:

The ornamental design for an automobile radiator, as shown.

THOMAS F. RAINSFORD.
